DESIGN FOR A MEMORIAL PLATE

Earl J. Mickelsen, Fremont, Nebr., assignor to Rudolph H. Ray, Fremont, Nebr., doing business as Ray Individual Mausoleum Company

Application April 29, 1937, Serial No. 69,049

Term of patent 14 years

To all whom it may concern:

Be it known that I, Earl J. Mickelsen, a citizen of the United States, residing at Fremont, in the county of Dodge and State of Nebraska, have invented a new, original, and ornamental Design for Memorial Plate, of which the following is a specification, reference being had to the accompanying drawing, forming part thereof.

I claim:

The ornamental design for a memorial plate, as shown.

EARL J. MICKELSEN.
